UNITED STATES PATENT OFFICE

CHARLES W. DESOBRY, OF INDIANAPOLIS, INDIANA, ASSIGNOR TO C. WILSON DE SOBRY, INC., OF INDIANAPOLIS, INDIANA, A CORPORATION

BOTTLE-CAPPING MACHINE

Application filed June 20, 1923, Serial No. 646,544. Renewed June 4, 1928.

This invention relates to a bottle capping machine.

The chief object of the invention is to simultaneously cap a plurality of bottles by 5 a battery capper construction.

The chief feature of the invention consists in the means provided for the accomplishment of the foregoing object.

Another feature of the invention consists 10 in the provision of a safety device associated with each individual capping mechanism, whereby in the event of any jamming of said individual mechanism, the safety device therefore will be actuated to release the 15 jammed mechanism from the battery operating means.

The full nature of this invention will be understood from the accompanying drawings and the following description and 20 claims.

In the drawings Fig. 1 is an elevational view of the discharge end of a universal bottle capping machine. Fig. 2 is a side elevational view thereof and of an endless 25 conveyor associated therewith, the latter being shown in section. Fig. 3 is a transverse sectional view of the bottle guides and filling and capping means showing the same by full lines in the non-filling and non-capping 30 position, the dotted lines indicating the position of said parts when adjusted to fill the smaller size bottles. Fig. 4 is a view similar to Fig. 3 of the same parts but with the same in the bottle filling and bottle 35 capping position. Fig. 5 is an enlarged sectional view of a portion of the bottle capping mechanism. Fig. 6 is a top plan view of a portion of the same and is taken in the plane of the line 6—6 of Fig. 5 and in the direction 40 of the arrows. Fig. 7 is a top plan view of a portion of the battery of the bottle capping mechanisms and is taken along the line 7—7 of Fig. 1 and in the direction of the arrows. Fig. 8 is an enlarged central 45 sectional view of a portion of the power means for securing relative movement between the bottles and the bottle capping and filling mechanism.

This invention relates to a bottle filling 50 and capping machine of the general type de-

scribed in the prior Patent No. 1,419,235, dated June 13, 1922.

In the drawings 10 indicates a framework supporting the uprights 11 between which is positioned the top or table 12. Each upright carries a U-shaped bracket 13 which slidably supports a bar 14, and said bar 14 extends along the machine parallel to the table top 12 and adjacent the end thereof is arched upwardly, as at 15, to form a passageway that will permit a bottle 16, carried by a belt 17 of a conveyor construction, and indicated generally by the numeral 18, to pass therethrough. Herein the pair of bars 14 carries a transferring bar 19 which moves transversely of the belt 17 to remove the bottles therefrom to the table 12. The bar closest to the advancing end of the conveyor construction carries upon its end a stop 20. This stop prevents the conveyor from positioning bottles adjacent the table top 12 while the transferring mechanism, comprising the bars 14 and transverse bar 19, is performing the transferring movement. Until the return of the transferring mechanism to 70 the position shown in Fig. 2, the conveyor is prevented from discharging any bottles, but after the stop 20 is removed from the path of the bottles, the same are permitted to advance along with the bar and subsequently be 75 removed therefrom and transferred to the table as described.

That portion of each upright 11 which projects upwardly above the table 12 is slotted at 21 and in said slot there is slidably supported a block 22. Each block 22 is connected to a plate 23 which supports the filling and capping mechanism. Reference will now be had to Figs. 1, 2 and 3 and in said figures it will be noted that the frame 10 supports a 80 motor 24 suitably connected to a driving worm 25, which in turn rotates a worm wheel 26 upon a shaft 27. The shaft 27 extends transversely of the machine and its free ends carry the cranks 28. The cranks 28 pivotally 85 support one end of links 29, the other ends of which are recessed or hollowed out as at 30 and are exteriorly threaded to receive aper-tured caps 31. The caps slidably support rods or links 32, the enclosed ends 33 of which 90

secure one end of the spring 34, the other end of which is secured by the cap 31. The other ends of the links 32 are pivotally connected to the slides 22. Thus, in the rotation of the shaft 27, by means of the motor 24, the slides 22 will be reciprocated to and fro in the slots 21, carrying with them the supporting plates 23 and, therefore, the supporting plates 23, together with the feeding and capping mechanisms will be reciprocated toward and away from the table 12 which carries the bottles 16 having the necks 35 and the mouths 36.

Each of the uprights 11 also rigidly supports the side plates 37 which lie adjacent to the plate 23. The plates 37 carry cams 38, see Fig. 2. Each cam 38 is pivotally supported by a side plate 37 and has one face engageable by an adjacent cam 39 carried by the adjacent and relatively movable plate 23. Another portion of the cam 38 is slotted at 40 and a pin 42 is receivable by one of the openings 43 in the adjacent bar 14. Pin 42 extends through the same and into the slot 40. Thus, when the plates 23 are reciprocated to and fro with respect to the table 12, the cams 39 will alternately tilt the cams 38 upon their pivotal supports to the right and left and thereby cause the same to reciprocate the bottle transferring mechanism, comprising the bars 14 and the transversely positioned bottle engaging bar 19 to transfer bottles from the conveyor 18 to the table 12 and return the mechanism for another supply of bottles. The cams 38 and 39 are so formed that intermediate travel of plate 23 is not effective. A plurality of holes 43 are provided so that for substantially the same amount of travel by the plate 23, the transverse rod 19 will move different distances, depending upon the size of bottle to be handled by the machine. The pin 42 is shown herein in the position to handle quart bottles, and herein provision is made for pints and half pints by the other holes 43.

Reference will again be had to Figs. 1 and 2 and also Figs. 3 and 4. In said figures it will be noted that the table 12 receives eight bottles 16, each having the necks 35 and the mouths 36. Positioned between the necks of the adjacent bottles there is a guide or separator 44, and these guides or separators are supported in depending relation by depending arms 45 secured to a transverse support 46, which support is carried at each end by a bracket member 47. The bracket members 47 are rigidly secured to the uprights 11 by the bolts 48 receivable by the openings 49 in the uprights 11. As shown clearly in Fig. 2, the plurality of openings 49 are provided to adjustably position the supporting brackets 47 carrying the spacing framework with reference to table 12. The spacing framework may be adjusted into a plurality of positions, herein shown as three in number and this is shown by the dotted lines in the left hand

portion of Fig. 1. The separator or spacing construction herein described thus is adapted to align the quarts, pints and half pints for passage through the machine beneath the fillers and cappers for filling and capping purposes by straddling the necks of the bottles. All milk bottles have standard mouths and necks. There is also provided, although not necessary in view of the separating framework previously described, the pair of retaining brackets in the form of angle irons 50 suitably supported by the table 12. Means for supplying but eight pints or eight half pints may be supplied in addition to bar 19 but the same is not necessary since the guides 44 limit the number of bottles and position the same.

The means for filling bottles is supported by and reciprocated with the plates 23. Herein said plates 23 each carries a wedge shaped tongue 51. These wedge shaped tongues extend inwardly towards each other and parallel to the table. A liquid containing tank 52 has a bracket 53 at each end, which bracket is complementarily shaped so as to receive the wedge-shaped tongue 51 and be supported thereby. An auxiliary tank 54 is supported at each end by the plates 55, each of which has a wedge-shaped groove so that said plates are supported by the wedge-shaped projections 51 and parallel to the tank 52. The tank 52 and the tank 54 are connected by one or more sliding or telescoping tubular connections, indicated generally by the numeral 56, and retained in adjusted position by the set screw 57 or equivalent means. Each of the tanks 52 and 54 supports a plurality of filling devices.

The first stage filler is associated with the auxiliary tank 54 and eight first stage fillers are provided to operate upon eight bottles simultaneously. Each first stage filler constitutes a tube 58 which has a suitably formed valve seat 59 at its upper and open end, which extends into the tank 54. A tube 60 is slidably supported in said tube 58 and its upper end is closed by a weight 61 fastened to constitute a valve member for closing the opening defined by the seat 59 of the tube 58. The tube 60 adjacent the closure valve member 61 is apertured so as to provide a lateral opening or a plurality of openings 62. The lower end of tube 60 is preferably closed as at 63 and adjacent said lower closed end is a lateral aperture 64 to secure lateral discharge of the fluid passing through the filling tube 60. The tube 60 carries a collar 65 with a plurality of radially projecting prongs or equivalent devices 66. These are of greater length than the diameter of the bottle mouth so that as shown clearly in Fig. 4 the pins 66 rest upon the top of the bottle 16 and tube 60 only enters the bottle mouth. In the continued movement of the plates 23 toward the table 12, after the pins 66 engage the bottle

top, the lateral apertures 62 are exposed to the interior of the tank 54 and permit the fluid, such as milk to discharge laterally into the bottle and prefill said bottles for the first stage filling. From the foregoing, it will be noted that each filling device herein described contains but one valve and it is opened by engagement with the bottle, and said opening movement occurs after the discharge is positioned within the bottle. Upon the reverse movement of the tank with respect to the bottles, the valve member 61 is seated by gravity upon the upper end of the open tube 58, thus cutting off communication therethrough and preventing further discharge of fluid from the tank 54 through the tube 60, other than that in the tube which continues to discharge into the bottle.

Although an adjustable construction is not illustrated, it will be readily apparent that the engagement of the tube 58 in the tank 54 will permit of bushing down said opening to receive smaller prefilling tubes, if desired.

The importance of the prefilling device is its springless construction, as well as the lack of separable plugs or valves and the lack of a plurality of valves.

Supported by the tank 52 is a similar number of filling and venting mechanisms, which final filling and venting mechanism is described in great detail in the copending application Serial No. 638,857, filed May 14, 1923. Herein said device is shown consisting of three tubular members telescopically positioned and provided with valve means at each end or adjacent each end for forming a springless filling construction with a bottle opening and a bottle closure therefor. In Figs. 3 and 4, 14 indicates the inner tube herein shown circular in cross section, which tube has a closed end 115 which supports a weight 116. The tube adjacent the upper end is suitably apertured, and herein two such apertures 17 are illustrated which permit the liquid in the tank or reservoir 52 to discharge laterally into the tube 114. Thereafter said liquid passes downwardly through said tube and out through the lower end thereof into the lower end of the intermediate tube 118. The intermediate tube 118 at its lower end is closed, as at 119, and adjacent said closure there is provided a laterally discharging mouth or port 120. The tube 118 is also provided upon opposite sides with parallel slots 121 which form guides for a pin 122. The pin 122, in the present invention, extends through the tube 114 and is not exposed to the interior thereof for a transverse tubular bearing 123 is provided in the tube 114 to prevent any leakage from the tube 114 through the guide slots 121. The guide slots 121 are always closed by the tube 114 irrespective of the latter's position, so that there is no lateral discharge from the lower end of the tube 114 through said slots.

The upper end of the tube 118 is exteriorly threaded at 124 and is receivable by the tubular bearing member 125 also having a threaded portion by which the latter is detachably secured to the tank 113 in the opening 126 thereof. The nut 127 has a threaded engagement with the tube 118 and locks the tube and the supporting member 125 to the tank 52. Member 125 is extended and projects upwardly beyond the end of the stationary tube 118 and forms a seat 127^a, which seat is adapted to receive the ball valve 116 constituting the weight carried by the tubular member 114. When the ball 116 is seated, the apertures 117 are closed and the top of the tube 114 is cut off from communicating with the tank 52.

A third tube 128 is telescopically associated with and mounted upon the tube 118 and constitutes the outer tube. The tube 128 is provided with a transverse opening 129 and a threaded opening 130, which openings are in alignment with each other. The pin 122, previously described, has one end seated in the opening 129 and the other end 131 is enlarged and threaded to form a head seatable in the threaded opening 130 of the tube 128. The tubes 114 and 128, therefore, move together and telescope the "stationary" tube 118. The tube 128 is recessed at 132 to form a seat for a cushion or shock absorber 133 which may be of rubber or any other suitable material.

The tube 128 is extended downwardly at 134 and the end thereof is beveled to form a valve seat. Herein the lower end of the stationary tube 118 is closed by the portion 119. Closure 119 is extended at 136 and is threaded to receive a conoidal valve member 137 having the valve surface 135. It is preferable to make the valve member 137 and the closure 119 separable for the reason that the volumetric displacement of the closure can be varied by putting on the extension 136 a smaller or larger conoidal end 137 without changing the tube.

There is provided in the tube 118 a channel 139 which does not extend from end to end. Said channel permits air within the bottle to pass upwardly through said channel 139 and outwardly therefrom during the filling or last stage operation. This permits filling under pressure. The channel 139 seats a key 140 which keys the tube 128, the latter having a complementary groove 141 therein, to the tube 118 to prevent rotative movement therebetween. The foregoing permits longitudinal and telescopic movement. The groove 141 is provided with a lateral discharge 143, which is preferably threaded to receive the threaded end of the prefilling and venting tube 144 which has a curved portion 145 and a discharge end 146. Suitable means, such as the set screw 147 is adapted to secure the mouth 146 intermediate the first

stage filling device and the last stage filling device just described. This intermediate position is shown by the dotted lines in Fig. 3.

While the bottle 16 is being filled to the top of the mouth, the bubbles of milk and air as well as considerable milk passes through the venting tube and discharges into the next adjacent bottle which, it will be remembered, has been partially filled by the prefilling device described in the fore part of the specification. Thus, there is provided a three stage filling construction for each bottle which is essentially a minimum number of stages that can satisfactorily be used and secure said complete bottle filling in the shortest amount of time. It is possible to completely fill a bottle in two stages by wasting the vintage, but herein three stages shorten the time of filling and also utilize what otherwise would be waste. The utilization of this venting and prefilling device also permits of filling under pressure which in turn will further shorten the filling period. The use of the first mentioned prefilling device further reduces the time of filling, since substantially about two thirds of the bottle may be filled by this prefilling device and possibly one sixth by the venting device and the remainder by the last stage and bottle mouth closing filler.

The sealing filler and venting device is operated by the engagement of said device upon the bottle mouth, which opens both valves of the device simultaneously and permits the fluid to be discharged into the bottle. The double valve construction also permits quick cut off with no drip. It is immaterial if there is dripping from the vent 146 or from the prefller mouth 64.

The means for applying a cap to the bottle so that the bottle is completely filled and capped ready for delivery, is illustrated in Figs. 1, 3, 4, 5, 6 and 7. Herein since the machine is shown adapted to simultaneously fill eight bottles at any one time, there is therefore provided a capping mechanism so constructed that it is operable to automatically and simultaneously cap a plurality of bottles, and herein eight bottles can be so accommodated.

Particular reference will be had to the before mentioned figures wherein the capping mechanism is there illustrated in detail. Herein a plate 70 is shown extending transversely of the machine and is suitably secured by the brackets 71 to the plates 37 stationarily supported by the uprights 11 previously described. The plate 70 is herein shown supporting a plurality of cap receiving reservoirs 72. Each reservoir 72, as shown clearly in Figs. 3 and 7, is substantially cylindrical in outline and is provided with a finger slot 73 to assist in inserting or manually removing caps 74 positioned therein. The caps 74 are circular and substantially the

same diameter as the inner diameter of the circular reservoir 72. The reservoir 72 is provided with a rearward extension 75, which extension straddles the channel-walled groove 76 formed in the plate 70 and extending transversely thereof. Slidably supported in said groove and retained therein by said base portion 75 is a slide 77, see Fig. 5, having tongue portions 78 seatable in the channels of groove 76. The plate 70 adjacent the groove 76 is apertured at 79 and in said aperture slidably receives a pin 80 carried by the plate 77. Each reservoir 72 has a discharge slot 81 and an oppositely positioned ejector receiving slot 82. The ejector plate 77 has an arcuate front face 83, and said arcuate front face passes through the slot 82, thereby engaging the lower-most circular cap generally of the paraffin or waxed paper type. Continued movement of said ejector slide 80 forces the cap outwardly through the opening or slot 81 and feeds said cap to a capping mechanism.

Since the machine is adapted to simultaneously handle eight bottles, there are provided eight capping reservoirs upon the supporting plate 70. Positioned beneath the plate 70 and substantially parallel thereto, is a reciprocating member or bar 84. This bar 84 is suitably apertured as at 85 to receive the several pins 80 carried by the individual reservoir ejector slides. The bar 84 is provided at each end with a pin 86, and this pin is carried by a slot 87 in the depending end of a lever 88 pivotally supported at 89 upon said stationary plate 37. The other end of the lever 88 is connected by a link 90 to one end of the cam lever 91 which is pivotally supported at 92 upon the plate 37. The lever 91 has the cam surface 93. A pair of cam plates 94 tilt the levers 91, which in turn tilt the levers 88 to move the actuator bar 84 to and fro beneath the plate 70. This to and fro movement carries with it all of the pins 80 of the several reservoirs.

In order that a jamming of one capper will not wreck the remainder of the capping mechanisms, a safety device is provided which is associated with the slide ejector. This is herein shown as a spring or yieldable clip 95 which is associated with the slot 85 to retain the pin 80 in engagement with the bar 84. Thus, on the forward or cap ejecting movement, the pin 80 bears upon the spring 95 and is carried with the bar 84 and the spring 95 to eject a cap 74 from the reservoir 72. In the event that the capper jams, or for any other reason the pressure required to eject a cap is so great that the spring 95 yields as shown by the dotted lines, such yielding will cause the yielding spring to be removed from the seats 96 in the notch 85. Thus the pin 80, the spring for which has been removed by excessive pressure, is not carried forwardly to eject the cap from the reservoir 130

and upon the return movement of the slide 84 said pin 80 is carried into the retracted position where it remains until such time as the obstruction is removed and the spring 95 again positioned in operative relation with respect to the bar 84 and the pin 80. This provision is not absolutely necessary, but is preferable for the reason that the caps frequently are not symmetrical and frequently 5 jam the capper, as will be understood by those skilled in the art. This provision furthermore permits the operation of the cappers in battery formation, which heretofore has been impossible. Likewise, this provision 10 does not seriously interfere with the operation of the machine for the reason that those bottles which pass beneath the capper and which are not supplied with caps, by reason of the jammed reservoir, are subsequently 15 supplied with caps by hand and the inspector upon observing that the bottles are coming through without caps will thereupon investigate and temporarily stop the machine until 20 the jam has been removed.

25 The capping mechanisms proper are shown clearly in Figs. 3, 4 and 7. In said figures the plate 23 carries a bar 97 which is apertured at 98 to receive a threaded sleeve or connection 99 locked thereto by the nut 100. The 30 connection 99 has a threaded engagement with one end of a threaded member 101 having a threaded interior and an enlarged lower end 102. Said threaded member 101 carries a threaded stem 103, the head of which 35 is reduced and carries a retaining cap or nut 104. The stem is provided with a quadruple thread so that it will spiral, twist or twirl a capping head 105. A reciprocatory hood construction includes a bottle centering head 106 and an upstanding guide tube 107 with the retaining flange 108 adapted to cooperate 40 with the enlargement 102. A portion 109, see Fig. 7, has a tongue and groove connection 110 with the reservoir construction and 45 serves to align the capper head with the reservoir. An extension 111 of the reservoir construction, and particularly plate 70, further serves to align the cap when the slot 112 registers with the slot 81, whereby a 50 cap 74 may be ejected from the reservoir into the bottle centering hood construction. The 55 capping head 105 carries a threaded or friction washer 113 and rotatably supported by said capping head 105 is a cap engaging member 69 suitably secured by means 68 to said capping head 105. One particular feature is the rotary movement of the cap seating means.

60 The operation of the various parts of the machine was described, when the description of the several parts was given. In brief the operation is as follows: The plates 23 are reciprocated towards and away from the table 12, which carries with it the tanks 52 and 54, the same having a slidable supply 65 connection 67, see Fig. 1. The battery of cappers, together with the battery of pre-filers and final fillers, are all carried with the plates 23 until the same engage the mouth of top of the bottles, whereupon continued movement of the plates 23 towards the table 70 12 causes the several valves to open in the filling device and causes the capper head to insert a cap 74 into the mouth 36 of a filled bottle. Should there be continued movement of the reciprocating mechanism, shown 75 particularly in Figs. 1 and 2, beyond that required to fill and cap the bottles, said additional movement is taken up by the spring 80 34, thus insuring substantially uniform pressure upon the bottles at all times. This construction, which is shown particularly in Figs. 1, 2 and 8 likewise permits the machine to fill and cap various heights of bottles such as half pints, pints and quarts, as shown by 85 dotted lines in Fig. 1 by permitting the slides 23 to move closer to the bottle 12 before engaging the bottle mouth. Additional movement of said plates thereupon causes the filling and capping of the bottles. It 90 95 will be noted from the foregoing that the filling and capping period for the smaller bottles is appreciably less than that for the larger bottles, and in this way one adjustment of the machine is eliminated.

It will be noted that except for the safety springs 95, see Fig. 6, and compensating springs, see Fig. 8, the machine is devoid of 100 springs.

The invention claimed is:

1. In a capping machine the combination of a plurality of cap reservoirs, a plurality of capping mechanisms relatively movable thereto, a single means for causing said relative movement for capping, a cap feeding member associated with each reservoir for supplying the capping mechanisms with caps, a single means for simultaneously actuating all cap feeding members, and a forcible yielding detachable connection between each cap feeding member and the last mentioned means securing automatic disconnection of the last mentioned connection when any cap feeding member is subjected to unusual resistance such as jamming.

2. In a bottle capper, the combination of a bottle support, a plurality of cap receiving reservoirs normally stationarily mounted with respect to said bottle support, a plurality of capping mechanisms each including a capping plunger positioned parallel to the reservoirs and relatively movable towards and away from said support, and an arcuately movable plunger supporting member, whereby each capping plunger will have simultaneous rotative and axial movement with respect to the bottle support, a cap feeding device for each capping reservoir for feeding caps to the capping plunger, a single means for actuating all of said cap feeding devices,

and a yielding forcible detachable connection between each cap feeding device and said single means.

3. In a bottle handling machine, the combination of a bottle supporting platform, a capping head support positioned thereabove, means for causing relative movement therebetween including a pair of telescopically associated members with an included spring therebetween, a capping mechanism including a plurality of cap receiving magazines arranged side by side above the platform, a similar number of capping heads associated with the support and above the platform, said magazines and heads being relatively movable, a cap projector associated with each reservoir for feeding a cap to the adjacent associated capping head in the relative movement, a common means for actuating all of said cap projectors, and a connection between each cap projector and said common means whereby said projector is automatically disconnected from said common means upon jamming.

In witness whereof, I have hereunto affixed my signature.

CHARLES W. DESOBRY.
